(57) **CLAIM**

The ornamental designs for vehicle front headlamp daytime running lights, as shown and described.

DESCRIPTION

FIG. 1 is a frontside perspective view of the vehicle front headlamp daytime running lights shown equipped on a passenger-side of a vehicle and on a driver-side of the vehicle;

FIG. 2 is a front view thereof;

FIG. 3 is a right side view thereof;

FIG. 4 is a left side view thereof;

FIG. 5 is a top view thereof;

FIG. 6 is a bottom view thereof;

FIG. 7 is a rearside perspective view thereof; and,

FIG. 8 is a rear view thereof.

The broken lines in the drawings indicate a boundary residing between claimed and unclaimed portions of the vehicle front headlamp daytime running lights. The broken lines form no part of the claimed designs. The claimed design is the lighter portion within the broken lines and the vehicle shown de-emphasized in half-tones depict environmental subject matter that forms no part of the claimed design.
